ATTORNEYS

UNITED STATES PATENT OFFICE.

HARVEY E. TYLER, OF CHICAGO, ILLINOIS.

MUFFLER.

Application filed June 13, 1925. Serial No. 36,911.

My invention relates to improvements in mufflers, and it consists in the combinations, constructions, and arrangements herein described and claimed.

5 An object of my invention is to provide a muffler that is adapted to break up the exhaust gases into fine streams so as to change the pulsating flow of the gases into a uniform flow, and to also cause these gases to flow 10 along the exterior wall of the muffler, whereby the gases will be cooled.

A further object of my invention is to provide a muffler of the type described in which the gases are projected against a cool metal 15 surface thereby agitating the gases so that all parts are effectively and quickly cooled.

A further object of my invention is to provide a muffler of the type described which is extremely simple in construction, durable 20 and efficient for the purpose intended.

Other objects and advantages will appear in the following specification, and the novel features of the invention will be particularly pointed out in the appended claims.

25 My invention is illustrated in the accompanying drawings, forming part of this application, in which

Figure 1 is a longitudinal view of my preferred type of muffler,

30 Figure 2 is a longitudinal view of a modified form of the device,

Figure 3 is a longitudinal view of another modified form of the device, and

Figure 4 is a section along the line 4—4 of 35 Figure 3.

In carrying out my invention I provide a muffler that comprises an outer casing 1 which is preferably cylindrical in cross section. In this casing are disposed two cup-shaped members 2 and 3 that are identical to each other. A description of one will therefore suffice for both.

The cup-shaped member has an open end 4 that faces toward the exhaust pipe 5. The 45 periphery of the open end 4 is of such a size as to snugly engage with the inner wall of the casing 1. The member 2 may be frictionally secured in place or may be spot-welded or the like.

50 The main body portion of the cup-shaped member is provided with a reduced peripheral wall 6 that is less in diameter than the peripheral wall 7. This forms a passageway 8 between the cup-shaped member and the casing 1. The wall 6 has openings 9 therein through which the exhaust gases flow as is

indicated by the arrows. As heretofore stated, the wall 6 is long and therefore keeps the exhaust gases in contact with the casing wall 1, whereby the exhaust gases are cooled. 60

The exhaust gases in passing into the muffler first flow to the rear of the cup-shaped member 2 whereupon they are caused to flow back upon themselves due to the wall 10. From this point the gases will flow through the 65 openings 9 and will strike the casing 1 when flowing in a direction at right angles to the casing. The gases will then be directed between the wall 6 and the wall 1 and will flow into the compartment 11 disposed between 70 the two cup-shaped members 2 and 3.

As heretofore stated, the cup-shaped member 3 is identical to the cup-shaped member 2 and therefore the same reference numerals will designate corresponding parts. The 75 cup-shaped member 3 will retard the flow of gases to the compartment 11 and will therefore force the gases against the casing wall 1 so as to effectually cool the gases. The 80 gases will flow from the compartment 11 through the openings 9 in the cup-shaped member 3 and thence to the end of the muffler where they will be ejected.

From the foregoing description of the various parts of the device, the operation thereof may be readily understood. The form of muffler just described is very simple in construction and provides a novel means for retarding the flow of gases through the muffler, for breaking the flow of gases up into 90 small streams, for causing these streams to play on the cool surface of the casing 1, and for keeping the gases in contact with this surface for a long time.

In Figure 2, I show a slightly modified form 95 of the device. In this form of the device, the casing 20 has a baffle plate 21 that stops the flow of gases through the casing. The casing also has openings 22 therein which are disposed quite a distance from the baffle 100 plate 21. The gases flowing through the casing 20 will strike the baffle plate 21 and will then be directed back on themselves to the openings 22. At this point the gases will pass through the openings in small streams 105 that extend at right angles to an outer shell 23. This shell of course is cool and will therefore cool the gases that come in contact therewith. The shell 23 is relatively long and provides a long passageway for the 110 gases. In this way I provide novel means for keeping the gases in contact with a cool

surface during the greater part of their passage through the muffler.

The ends of the shell 23 are bent inwardly and are secured to the casing 20. The shell 5 23 projects beyond the baffle plate 21 so as to carry the gases beyond the baffle plate 21. Openings 24 are provided in the casing 20 so as to permit the gases to flow from the shell 23 back into the casing 20. The gases 10 will thereupon be expelled from the muffler.

This form of the device has the same object in view as the preferred form which is to keep the hot gases against a cool surface for the greater part of the passage of the 15 gases through the muffler. The other object of the modified form of the device which is similar to the preferred form of the device is to provide a muffler which is simple in construction and made from very few parts.

20 In Figure 3 I show still another modified form of the device. In this form of the device, the casing 30 is provided with a baffle plate 31 of a peculiar shape. The baffle plate 31 has one of its ends secured to the casing 25 30 for a portion of its length and then the baffle plate is bent at an angle to the longitudinal axis of the casing so as to finally bear against the surface of the casing 30 disposed diametrically opposite the part of the casing 30 receiving the first end of the baffle plate.

The inclined portion 32 of the baffle plate is provided with curved edges 33 (see Figure 4) that are spaced slightly from the casing 30 so as to provide small spaces 34 through 35 which the gases are forced. The gases in passing the inclined portion 32 are forced against the outer casing 30 and are thereby cooled.

The baffle plate 31 is again bent at 35 in a 40 manner similar to that of 32. The shape of the portion 35 therefore needs no further description since the shape of the portion 32 has been clearly described. The gases passing

the portion 35 are forced against the outer casing 30 and are cooled, and furthermore the gases in passing the portion 35 restrict the flow of gases through the compartment 36 formed by the portions 32 and 35. This restricted movement of the gases forces the gases against the outer casing 30 which also aids in cooling the gases. The portions 37, 38, and 39 of the baffle plate 31 are curved so as to conform to the curvature of the casing 30. If desired the baffle plate 31 may have as many inclined portions 32 and 35 as needed so as to provide an efficient means for cooling the gases and for causing the gases to flow uniformly from the muffler. 45 50 55

It will thus be seen that instead of having a core of hot gases which pass through the muffler with very little cooling as in the ordinary type of muffler, I provide means by which the gases are caused to impinge against a cool metal surface thereby quickly reducing the temperature of the gases, and thus 60 65 causing less noise when the gases are finally expelled into the atmosphere.

I claim:

A device of the type described comprising a casing, a relatively long cup-shaped member 70 having an open end, a closed end, and a plurality of openings circumferentially disposed adjacent the open end, a relatively short enlarged portion rigidly secured to the inner wall of said casing, and a partition connecting said enlarged portion to said relatively long cup-shaped member, said cup-shaped member being adapted to cause gases of combustion to back up on themselves and pass through said openings, said cup-shaped member being disposed in close proximity to the inner wall of said casing, whereby the gases of combustion passing through the openings will be held against the inner wall of said casing and become cooled. 75 80

HARVEY E. TYLER.
